UNITED STATES PATENT OFFICE

2,456,312

VENTILATOR

Bertie K. Paget, Detroit, Mich.

Application May 24, 1945, Serial No. 595,547

6 Claims. (Cl. 98—42)

1

This invention relates to ventilators for industrial purposes and more particularly to ventilators of the multi-cell or multi-section unit type, such as disclosed in my Patent No. 2,134,143, October 25, 1938, and my application filed February 7, 1944, Serial No. 521,303, of which latter the present application is a continuation-in-part.

It is among the objects of my invention to provide a ventilator having the advantages with respect to efficiency and operation of said patented ventilator and one which will provide a number of improvements relating to lowered costs, simplicity in construction, flexibility of use and improved air flow and operating characteristics.

More particularly it is an object of my invention to provide a multi-cell or multi-section unit ventilator wherein a series of baffles and dampers are arranged with respect to each other within the unit so that the dampers in their open position function to prevent wind-blown air from entering the interior of the building which is being ventilated.

It is a further object of my invention to provide continuously extendable multi-cell of multi-section unit wherein a series of baffles and dampers are so arranged with respect to each other, within the unit, that the path of the air or gas moving upwardly through the ventilator between a series of pairs of vertically superposed baffles and dampers is essentially parallel to the path of air or gas moving upwardly through all of the other pairs of baffles and dampers, so as to provide a passageway between each cooperating pair of baffles and dampers which will be especially conducive to a laminated flow of air or gas upwardly through the ventilator.

It is a further object of the invention to provide a ventilator of a multi-cell type, wherein a series of parallel, inclined baffles are arranged near the bottom of the ventilating unit, and another series of parallel, inclined baffles disposed above the first mentioned series, and inclined in an opposite direction to that of the first series of baffles. A series of pivoted dampers are arranged above the second series of baffles so that the dampers may be disposed in their open position at an angle to the baffles therebelow which will prevent rain from entering the building being ventilated.

It is a further object of my invention to provide a ventilator according to the preceding objects in which the baffles and dampers are provided with drainage means constructed and arranged to carry drainage water along the lower

2

edges of the dampers and baffles, transversely of the opening being ventilated.

It is a further object of my invention to provide a multi-cell ventilator according to the preceding objects with an improved damper-operating mechanism constructed and arranged to facilitate the installation of the unit and to house the damper-operating mechanism within the unit in a way that will contribute to the ease of operation, low cost and long, efficient life of the ventilating unit.

It is a further object of my invention to provide a ventilator according to the preceding objects in which the drainage means for the baffles is constructed and arranged to accommodate and carry away moisture resulting from such condensation as may form on the lower side of the baffles and dampers as well as rain water falling upon the upper side of the baffles.

Further objects and advantages relating to low manufacturing costs, ease in handling, installation, and sturdiness in construction will appear from the following description and the appended drawings, wherein:

Figure 1 is a top plan view of a multi-cell unit constructed according to my invention;

Figure 2 is a longitudinal vertical sectional view of Figure 1;

Figure 3 is a transverse sectional view of the unit;

Figure 4 is a perspective view of a baffle element;

Figure 5 is a perspective view of a damper element;

Figure 6 is a perspective view of a modified baffle element; and

Figure 7 is a detail view illustrating outlet opening in end walls of casing.

In attaining the objects above referred to and the advantages associated therewith, it has been necessary to surmount the disadvantages of many of the commercial units wherein the air streams rising up underneath the ventilator are bifurcated and split into two parts before passing into the open air. With ventilators of this type the free area of the ventilator, or the area of the opening that can be used, is approximately 40% of the area of the casing.

Now, with the present invention a new principle has been achieved. The air streams, rising up underneath the ventilator, are nested together and segmentally divided in elbow-shaped streams by the two series of oppositely disposed inclined baffles and inclined dampers, so that the streams of air passing through

the ventilator take a zig-zag-zig course with all of the several streams separated from each other only by the narrow thickness of the baffles and dampers. This produces a larger ventilating area within the casing, since the usable space is considerably increased as substantially all barriers to the flow of air are eliminated with the result that there is provided 80% to 95% free area within the limits of the casing.

With the present invention, by providing a casing with a series of inclined baffles arranged adjacent the bottom of the casing, and a series of inclined baffles disposed in the casing above the first series of baffles and inclined in a different direction to that of the first series of baffles, and a series of dampers mounted above both series of baffles, so that the dampers in their open position are inclined in a direction opposite to that of the second series of baffles, a series of vertical ventilating passageways are produced throughout the length of the casing. The series of baffles and dampers are disposed transversely of the casing and preferably in staggered relation with respect to each other so that the ends thereof are in spaced relation, and resulting in providing a series of zig-zag-zig vertical passageways for the air, which passageways have communication with each other at the adjoining ends of the rows of baffles and dampers.

A marked advantage in the separation of downwardly moving rain from the upwardly moving ventilating air stream follows from the staggered arrangement of inclined baffles above referred to. It will be appreciated that as the ventilating air reaches the outlet of the first inclined section of its travel upward it is divided into two parallel streams. The two parallel streams move through the next section of travel upward in a direction nearly normal to the section first travelled. A similar result is accomplished as the air streams reach the third section of travel defined by the dampers. Thus it will be observed that as the air moves upwardly through the ventilator from the inlet of the first section to the outlet of the third section each separate stream is twice divided and partakes of two changes in direction.

The dampers and baffles are provided with means for draining the rain or water crosswise and lengthwise thereof to the roof of the building. Therefore, by this invention the air from the building has substantially unrestricted flow to the atmosphere, and the rain entering the ventilator must contact some or all of the series of baffles and dampers and is prevented thereby from entering the building as it will be drained from the baffles and dampers to the roof of the building.

Referring to the drawings, Figure 2 illustrates a multi-cell unit, which comprises a casing 10 composed preferably of a lower and an upper section 11 and 12. The casing 10 is provided with parallel side walls 13 and end walls 14. Generally the unit is arranged on a longitudinally extending, rectangular opening formed in the roof of the building to be ventilated and the unit shown in Figures 1 and 2 is proportioned to ventilate such an opening.

It will be appreciated that the units may preferably be constructed in multiples, of such sizes, as to length and width, as best suited for shipping and installation, and for adaptability to the particular shape or construction of roof. Also, the units may be installed longitudinally, crosswise, and otherwise on the roof and at various angles or inclinations to conform to the contour of the

roof. When installed in multiples, the units may be so associated with each other that the mechanism for operating one set or series of dampers may be connected to the other series of dampers of the other units and thereby all series of dampers may be actuated by a single operating mechanism.

The unit 10 includes two series of inclined baffles 15 and 16, extending transversely of the unit. 10. The ends of each of the baffle plates 15, 16 are preferably formed with flanges 17 which may be secured to the side walls 13, 13 by rivets, spot-welding or otherwise. The baffle plates 15 are positioned in the lower section 11 of the casing 10 while the baffle plates 16 are located directly above the baffle plates 15 in the upper section 12 of the casing, these latter baffle plates 16 are inclined in a direction opposite to the direction of inclination of the baffles 15 and are so disposed 20 that the lower ends thereof are offset with respect to the upper ends of the baffles 15. The lower or bottom edge of each of the baffles 15 is provided with an integrally formed drainage device in the form of a curved bottom wall or 25 trough 18. The elements 18 catch any water such as rain that may drain down the surface of the baffles and direct the water longitudinally of the baffles to the side walls of the casing 13 where it is discharged through a notch 20 into a trough 24 30 formed by the lower edge of the side walls 13 and the longitudinally extending lower rail or flashing strip extension 22. The lower edge of the walls 13 and 14 of the section 11 is apertured or slotted as at 23 to permit the drainage water in 35 the trough 21 to flow outwardly from the sides and ends of the casing onto the roof of the building.

The lower edges of the baffles 16 are provided with outwardly projecting lips or flanges 19, for 40 the purpose of reinforcing the baffles, and serving as deflectors or riffles to insure that the incoming rain will be slowed up or retarded and will spill gently over the edge of the lips 19 to arrive eventually at the drainage trough 18 at the bottom of the lower series of baffles.

The baffles 16 and flanges 19 are provided with notches 40 found at the ends of the flanges 19 and at the lower edge of the baffles adjacent the side walls 13, so that any moisture or water may flow 50 longitudinally of the flange 19 onto the side walls 13 and thence down the side walls to the drain troughs 21.

Arranged above the baffle plates 16 of section 12 is a series of damper elements 24 secured to 55 transversely extending damper rods 25 and are preferably proportioned at either side of their fulcrum. The damper rods are rotatably supported in bearings 26 carried by the side walls 13. The dampers in their open position, as shown 60 in Figure 2, are disposed in planes approximately normal to the planes of the baffle plates therebelow, and as illustrated assume an inclination in substantially the same direction and parallel to the baffle plates 15 of section 11. The pivot points of the dampers are spaced from and arranged with respect to the plane of the upper edge of the baffles 15, 16 so that the dampers and baffles acting together prevent rain from entering the building being ventilated.

It will be seen that there is a staggering relation 70 between the two series of baffles and the series of dampers, so that the adjoining ends are in spaced relation, so that there is an overlapping of the ends of the baffles of one series by that of 75 another series, and a similar relationship between

the baffles and the series of dampers. It will accordingly be appreciated that the dampers in their open position function to change the direction of flow of air and prevent entrance of rain the same as though they were another series of fixed inclined baffles. This arrangement provides and insures a directional flow vertically of the air from the building outwardly through a zig-zag-zig course, and establishes communication between the several streams of air at the adjoining ends of the baffles and dampers, so that the several streams are nested together and are separated only by the thickness of the baffle plates and dampers. Should rain be falling during the ventilation period, the rain would contact the dampers and baffles and be directed over the surfaces thereof and collected by the lips or flanges 19 and 26 of the baffles 16 and dampers respectively, and troughs 18 and 21 caused to drain transversely of the casing and lengthwise of the baffles and dampers where the rain or water would be delivered to the troughs 21 of the casing 10. The water will flow down the side walls 13 of the casing from the dampers 24 and baffles 16 conducted thereto by the flanges 19 and 26 to the troughs 21 thereof, while at the same time the rain water would spill over the lips 19 and 26 onto an adjacent lower baffle and be finally collected and discharged by the troughs 18 and 21. In this manner there is a separation of any rain water from the vertically flowing air stream and at the same time insuring against any water entering the building being ventilated.

As shown, the lower series of baffles 15 are preferably of greater transverse width than the width of the baffles 16 and dampers 24 and are the only baffles disposed in the lower section 11 of the casing 10. This is important for the purpose of providing a sufficient area for the water entering the casing to ricochet or bounce and eventually to be collected in the troughs 18 and then delivered to the troughs 21.

The preferred position of the dampers 24 is at the top of the unit. This because condensation, occurring when the dampers are closed in the winter, with cold air outside and warm air inside, will, when the droplets of condensation are formed, drip down onto warm baffles, themselves bathed on all sides by warm air and hence free of condensation, and such warm baffles will then conduct the condensation to the troughs 18, 19, 26. Of course, the dampers could be placed or positioned where the baffles 16 are located and these baffles 16 located at the top of the section 12, and like results would be attained.

As illustrated in Figures 1 and 2 the several dampers 24 are connected to one or more rails 27, extending longitudinally of the casing 10 by ears 28. Pivot pins 29 passing through the ears 28 and rails 27 for pivotally connecting the dampers to the rails. Journalled at one end of the casing is a rock shaft 30 to which each of the rails are connected by links 31, 32. The rock shaft is adapted to be operated by a wheel 33 through suitable gearing, not shown, for opening and closing the dampers. The dampers when in the closed position shown in Figure 1 afford means for keeping snow, ice and other foreign matter from entering the ventilator.

The dampers 24 are provided with lips or flanges 26 at their respective ends, with a lip at one end extending at an angle from the damper while the other lip extends at an angle in the opposite direction. The lips 26 engage with adjacent dampers when the dampers are in a closed

position to provide a proper seal between the dampers, and the lips or flanges on the end dampers engage with a flange 34 on the wall of the casing.

5 This is accomplished by having the dampers proportioned at either side of their pivot, and that when the dampers are in open position, the dampers and baffles are proportioned with respect to each other to prevent rain from entering the opening between the lower edges of the baffles.

10 The lower section 11 of the casing 10 is provided across one end with a downwardly inclined skirt or flange 35 for directing any water or moisture that may be discharged thereon from the dampers to the lower series of baffles.

15 In the construction of baffle 15, 16 of Figure 6, the lower edge thereof may be provided with an integrally formed drainage device comprising the side wall 38 and a curved bottom wall or trough 18. The side wall 38 is formed with a series of 20 staggered louvers 39 so that moisture condensed on the lower side of the baffle may run down said lower side and into the louvers 39 and thence into the trough 18 formed by the curved bottom wall. Rain water impinged upon the upper side 25 of the baffle may run downwardly into the trough formed by the bottom wall 18.

What I claim is:

1. A ventilator comprising a rectangular substantially horizontally disposed casing, a series 30 of inclined baffles mounted near the bottom of the casing dividing the upwardly moving ventilating air into a series of parallel air streams, a second series of inclined baffles mounted in the 35 casing above the first named series and offset horizontally with respect thereto and inclined in a direction opposite to the inclination of said first mentioned series of baffles so as to divide the ventilating air at the outlet of the said first series, and a third series of inclined baffles above the 40 second series similarly offset to divide the ventilating air at the outlet of the second series and conduct such air to the atmosphere, means associated with at least one series of baffles for 45 collecting any water flowing over said baffles and means for disposing of the water collected by said first-mentioned means.

2. A ventilator comprising a casing having side walls and open top and bottom walls, a series of 50 inclined baffles mounted on the side walls near the bottom wall of the casing for dividing the upwardly moving air into a series of parallel air streams, a second series of inclined baffles mounted in the casing above the first named 55 series and offset horizontally with respect thereto and inclined in a direction opposite to the inclination of said first mentioned series of baffles so as to divide the air streams at the outlet of said first series and deflect the flow of the air streams at an angle to the flow of air through the first series of baffles, and a third series of inclined baffles mounted in the casing above the second series and similarly offset to divide the air streams at the outlet of the 60 second series of baffles and deflect the flow of said air streams at an angle to the flow of air through the second series and conduct the air streams therethrough to the atmosphere, means associated with at least one series of baffles for 65 collecting any water flowing over said baffles and means for disposing of the water collected by said first-mentioned means.

3. A ventilator comprising a casing having side and end walls and open top and bottom walls 70 producing a passageway lengthwise and trans-

versely of the casing, a series of substantially parallel inclined baffles extending transversely of the casing, another series of substantially parallel inclined baffles extending transversely of the casing and disposed above the first series with the baffles thereof inclined in a direction opposite to the direction of inclination of the first series of baffles, a series of dampers located in the casing above said second series of baffles for forming a closure for said casing when in closed position and disposed at an inclination when in open position at an angle to the position of said second series of baffles, said series of baffles and dampers each having the edges thereof in overlapping relation, said series of baffles and dampers thereby producing a plurality of air passages through said casing so that air flowing through said casing flows in a plurality of nested streams which have communication with each other at the ends of said baffles and dampers means on said first mentioned series of baffles for collecting water flowing over said baffles, and means for disposing of the water collected by said first-mentioned means.

4. A ventilator comprising a casing having side and end walls and open top and bottom walls, a series of substantially parallel inclined baffles extending transversely of the casing, another series of substantially parallel inclined baffles extending transversely of the casing and disposed above the first series with the baffles thereof inclined in a direction opposite to the direction of inclination of the first series of baffles, a series of dampers located in the casing above said second series of baffles for forming a closure for said casing when in closed position and disposed at an inclination when in open position at an angle to the position of said second series of baffles, said series of baffles and dampers each having the edges thereof in spaced relation to the edges of an adjoining series of baffles and dampers, and having the edges thereof in overlapping relation, said series of baffles and dampers thereby producing a plurality of air passages through said casing so that air flowing through said casing flows in a plurality of nested streams which have communication with each other at the ends of said baffles and dampers, and means associated with a series of baffles and dampers for collecting any water flowing over said baffles and dampers and means for disposing of the water collected by said first mentioned means.

5. A ventilator comprising a casing having side and end walls and open top and bottom walls, a series of substantially parallel inclined baffles extending transversely of the casing, another series of substantially parallel inclined baffles extending transversely of the casing and disposed above the first series with the baffles thereof in-

clined in a direction opposite to the direction of inclination of the first series of baffles, a third series of substantially parallel inclined baffles located in the casing above said second series of baffles and disposed at an inclination to the position of said second series of baffles, said series of baffles collectively producing a plurality of tortuous air passages therebetween and through said casing so that air flowing through said casing flows in a plurality of nested streams, one of said series of baffles being pivotally mounted in said casing for forming a closure therefor when said baffles are in closed position and performing as baffles when in open position, means associated with the baffles of at least one series for collecting any water flowing over said series of baffles, and means for disposing of the water collected by said first mentioned means.

6. A ventilator comprising a casing having side and end walls and open top and bottom walls, troughs disposed along the lower edges of said side walls, said side and end walls provided with openings communicating with said troughs for draining water from the troughs to the roof of the building, a series of substantially parallel inclined baffles extending transversely of the casing, another series of substantially parallel inclined baffles extending transversely of the casing and disposed above the first series with the baffles thereof inclined in a direction opposite to the direction of inclination of the first series of baffles, a third series of substantially parallel inclined baffles located in the casing above said second series of baffles and disposed at an inclination to the position of said second series of baffles, said series of baffles collectively producing a plurality of tortuous air passages therebetween and through said casing so that air flowing through said casing flows in a plurality of nested streams, and means on said baffles for collecting the water flowing over said baffles and for conducting the water to the sides of the casing for delivery to the troughs on the side walls of the casing.
